LIQUID DISPENSER

Stewart D. Swihart, Fort Wayne, Ind., assignor
to Fred C. Zieg, Fort Wayne, Ind.

Application August 18, 1941, Serial No. 407,348

6 Claims. (Cl. 221—76)

This invention relates to improvements in liquid dispensers of a type used for periodic delivery of small limited quantities of liquid and variable to an extent according to manipulation upon each operation, such device as is useful in tonsorial and beauty parlor establishments where small quantities of various liquid preparations are required for instant use.

An object of the invention is to afford a dispensing attachment for a liquid container, said attachment and the container being formed so as to be connected together and become operable for withdrawal of small quantities of liquid from the container when the attachment is completely seated and secured on the container, and become inoperative when loosely or partially connected.

Another object of the invention is to provide a dispensing appliance connected separably with a liquid container, both of which are so constructed as to be co-operative when connected together, and non-interchangeable with other differently constructed similar appliances and containers, the purpose being to circumvent use of parts of the instant invention indiscriminately with parts of other apparatuses.

And a further object of the invention is the provision of a dispensing device having a suction tube and related parts arranged so that when the body of the dispensing device is secured to a liquid container communication between the tube and the discharge channel of the dispensing device is established to render the apparatus operative.

Other objects and advantages of the invention appear in the following description.

An illustrative embodiment of the invention is shown in the accompanying drawing, in which:

Fig. 1 is a side elevational view of a structure in which the invention is incorporated, parts thereof being broken away; and

Fig. 2 is a similar view of the dispensing appliance shown in Fig. 1, attached to a liquid container in operative position, portions being broken away.

The illustrative embodiment of the invention consists of a detachable dispensing device formed of a base member 1 having a tubular neck 2 and an internally threaded lower end 3 constituting a cap adapted to fit onto the externally threaded neck 4 of a liquid container 5, there being a vent opening 6 made in the base that affords an inlet for air to the container for the relief of vacuum created therein as liquid from the container is withdrawn by the appliance.

Upon the neck 2 is closely fitted a valve casing 7, the lower end portion of which has a bore af-

fording a chamber 8 therein above the neck of the base, said bore having a continuation 9 of reduced diameter that extends from said chamber through the top of the casing. In the lower end of the smaller bore is securely positioned a tubular valve seat 10 on which rests an outflow check-valve 11 that is normally closed. A second tubular valve seat 12 is securely positioned in the small bore in the casing upon which rests a second outflow check-valve 13 that is normally closed. The lower end of the tube 12 terminates at a point spaced from the check-valve 11 and has made therein a notch 14 whereby the check-valve 11 is prevented from closing the tube 12 when the check-valve 11 is unseated by outflow of liquid through the tube 10.

A spout 15, preferably in the form of a goose-neck, is secured in the upper end of the small bore in the casing, its proximal end terminating at a point above the check-valve 13, and has made therein a notch 16 whereby the check-valve 13 is prevented from closing the spout when said check-valve 13 is unseated by outflow of liquid through the tube 12.

A hollow stem 17 is secured in one side of the casing 7 that has communication with the bore of the tube 12 through a passageway 18 therein, and the outer end of said stem has secured thereon a compressible bulb 19, upon manipulation of which, alternate outflow through the spout and inflow through the tube 10 of fluid past the check-valves 11 and 13 takes place.

The passageway 18 in the tube 12 is located preferably at a point above the axis of the stem 12 so that seepage of liquid from the bulb back into the tube 12 is limited and loss of prime is thus substantially averted. This arrangement is desirable especially when the appliance is left idle for a considerable period of time between operations.

Preferably, a metallic band 20 is disposed about the valve casing 7, through one side of which the stem 17 projects, the band serving as an ornamentation as well as to strengthen the casing.

A suction tube 21 is provided for the dispenser, the tube being positioned so as to extend up through the bore of the neck 2 of the base and is provided with a concentric head 22 secured on its upper end which is surmounted by an apertured gasket 23, the head and gasket being disposed within the chamber 8 and axially movable therein. Upon the tube is loosely disposed a sleeve 24, the upper end of which has an internal flange 25 through which the tube 21 loosely extends, and a shoulder 26 on the tube has engage-

ment with said flange, the shoulder being located on the tube at a point spaced from the head 22 so that relative axial movement of the sleeve and the head is positively limited in one direction, and a compression spring 21 is disposed on the tube 21 between said sleeve and head by which relative movement thereof in the opposite direction is yieldingly resisted.

Preferably, the liquid container 5 is in the form of a bottle, the neck of which is partially closed by an integral choke 5' having a central opening 5" proportioned so as to receive loosely therethrough the tube 21 when the dispensing appliance is in operative position on the container. After the cap is screwed down completely onto the neck of the container the sleeve 24 bears upon the choke 5' thereof and exerts pressure against the spring 21 with consequent upward thrust of the head 22 and overlying gasket 23. In this manner is effected a sealed connection between the suction tube 21 and the lower end of the discharge channel 28 that continues therefrom through the tubes 10 and 12 and spout 15.

Operation

In use of the invention, the containers are filled through their openings 5" with a selected liquid preparation and capped in the usual manner by ordinary seals (not shown) for distribution, and the dispensers are furnished with the containers separately at the time of distribution or subsequently as renewals are required.

Preparatory to the dispensing operation the cap by which the container is initially closed is removed; the tube is inserted down through the opening 5" and the base is screwed down tightly onto the threaded neck of the container, whereupon the sleeve 24 is arrested by having contact with the choke 5' causing compression of the spring 21 and consequent sealing of the suction tube with the discharge channel whereby free leakproof communication for the liquid is established through the suction tube and discharge channel. The apparatus then is in condition for carrying on dispensing operations. By compressing the bulb 19 its contained air is expelled through the tube 12 past the check-valve 14 out through the spout 15, and the bulb, as it is permitted to expand, causes vacuum in the discharge channel between the check-valves 14 and 13 and consequent flow of liquid from the container up through the suction tube past the check-valve 14 and entrapment of a quantity of the liquid in the channel between said check-valves. When the bulb is again compressed the entrapped liquid thereupon is forced past the check-valve 13 out through the spout and utilized.

The container, after its liquid content has been exhausted, is disconnected from the dispenser and replaced by another filled container.

Because of the peculiarities of the container with its apertured choke, the sealing relation between the suction tube and the discharge channel, and the sleeve in its operative relation between the choke and the discharge tube structure 65 when the dispenser is connected with the container, interdependence is established between the dispenser and the container for successful operation of the apparatus.

It is preferable that the pitch of the threads on the container neck and in the base of the dispenser be of an odd pitch distinguishable from the pitch of that of the threads on similar containers so as to circumvent use of the dispenser with unauthorized container replacements.

Variations from the particular construction above disclosed may be resorted to by the exercise of skill in the art, without departure from the spirit or scope of the invention, and the following claims are intended to be inclusive of such variations.

What I claim is:

1. A liquid dispensing apparatus including a container having an externally threaded neck provided with a choke central opening, a dispenser having a vented base threaded to fit said neck, a valve casing secured concentrically on said base having an axial bore the lower portion of which forms a chamber, the upper portion of said bore constituting a discharge channel, two valve seats located in said channel at points spaced apart from each other each provided with an outflow check-valve, a spout having communication with the upper end of said channel, a hollow stem having communication with said channel at a point between said check-valves and provided with a compression bulb, a suction tube having on its top a gasketed head movable in said chamber, a flanged sleeve on said tube having relative movement thereon limited in one direction; and a compression spring on said tube between said sleeve and head, the arrangement being such that when the tube is inserted through said choke opening into the container, and the base is screwed into place on the neck, said sleeve has contact with said choke causing sealed connection between said tube and discharge channel.
2. A liquid dispensing apparatus including a container having a neck with an apertured choke, a dispenser provided with a base detachably connectable to said neck, a valve casing secured on said base provided with an axial bore to form a chamber in its lower portion and a continuation of reduced diameter constituting a discharge channel, two outflow check-valves located in said channel at points spaced apart from each other, means communicating with said channel at a point between said check-valves to create vacuum or pressure alternately therein, and a suction tube having a head movable in said chamber, and provided with means engageable with said choke when the base is in place on the container to cause sealed connection between said tube and said channel.
3. A liquid dispensing device constituted of a liquid container and a dispenser, said container having a neck with an apertured choke, said dispenser consisting of a valve casing provided with a vented base detachably connectable with said neck, said casing having in its lower part a chamber and in its upper portion a discharge channel extending from said chamber and terminating in a spout, outflow check-valves disposed in said channel spaced apart from each other, means communicating with said channel at a point between said check-valves to cause flow of fluid in said channel past said check-valves, a suction tube provided with a head located movably in said chamber adapted in one position to form sealed connection between said tube and channel, and means on the tube engageable with said choke to move said head to sealing position when the tube is inserted through the aperture in the neck and the base is secured in place on said neck, the arrangement being such that operation of the apparatus is dependent upon the connection between the tube and channel being sealed.
4. A liquid dispensing device constituted of a liquid container and a dispenser, said container

having an apertured choke, said dispenser having a body provided with a base detachably connectable with the container concentric with the aperture in the choke, and provided with a vent opening, there being a chamber and a contiguous discharge channel in said body terminating in a spout, outlet check-valves spaced apart from each other located in said channel, means to create flow of fluid past said check-valves through said channel, and a suction tube provided with means movable in said chamber and engageable with said choke whereby sealed connection of the tube and channel is effected upon insertion of the tube through the choke and securing said body in place on the container.

5. A liquid dispensing device constituted of a liquid container and a dispenser detachably connectable therewith, said container having an apertured choke, and said dispenser having an outflow check-valve controlled discharge channel and a member for inducing flow of fluid through said channel, and a suction tube insertable through the aperture in said choke provided with

10 compressible means extending movably into the dispenser body engageable therewith and said choke when the dispenser is secured in place on the container to seal connection between said tube and channel.

15 6. A liquid dispenser constituted of a body attachable to a liquid container that has a neck provided with a choke with an opening therein, said body having a vented chamber in its base and an outflow check-valve controlled discharge channel leading from said chamber terminating with a spout, a suction tube extending loosely through said opening into the container and projecting into said chamber provided with a head and means in connection therewith wherefore to automatically close communication between the chamber and said channel when the body is in place on said container, and means having communication with said channel to cause outflow of fluid from said container through said tube, channel and spout.
